UNITED STATES PATENT OFFICE.

LEO CANDA, OF CINCINNATI, OHIO.

DESIGN FOR A CARD-DISPLAYING CABINET.

SPECIFICATION forming part of Design No. 32,260, dated February 20, 1900.

Application filed January 11, 1900. Serial No. 1,148. Term of patent 3½ years.

To all whom it may concern:

Be it known that I, LEO CANDA, a citizen of the United States, and a resident of Cincinnati, Hamilton county, State of Ohio, have invented and produced a certain new and original Design for a Card-Displaying Cabinet; and I do declare that the following is a description thereof sufficiently clear, full, and exact to enable others skilled in the art to which it appertains to make and use the same, attention being called to the accompanying drawings, with the reference-numerals marked thereon, which form also a part of this specification.

The subject of this invention relates to a cabinet which is provided in its front with openings within and behind which rows of cards may be displayed.

The object is to increase the usefulness, as well as to improve the appearance, of such a cabinet by certain proportions of sizes, number, and arrangement of parts and configurations thereof, all as hereinafter described, and illustrated in the accompanying drawings, in which—

Figure 1 is a front view of the cabinet embodying my design, and Fig. 2 is a side view of Fig. 1.

The cabinet consists of two parts, one above the other, and of which the upper part (indicated by 6) is higher and broader than the lower part, (indicated by 7.)

The front of the cabinet is horizontally subdivided by rows of openings 3 and intervening fields or panels 4, all arranged one below the other, as shown. Of these rows of openings those in the front of the upper and larger part of the cabinet are correspondingly larger and have each two openings arranged side by side with a space between.

The cabinet is suitably supported on a column 8, centrally below part 7 of the cabinet and rising from a base 9.

Having described my invention, I claim the same, as follows:

The design for a card-displaying cabinet, substantially as shown and herein described.

In testimony whereof I have hereunto set my hand this 9th day of January, 1900, in the presence of two witnesses.

LEO CANDA.
